HEAD FOR GATE OPERATING MECHANISM FOR HOPPER CARS

George B. Dorey, Westmont, Quebec, Canada, assignor to Enterprise Railway Equipment Company, Chicago, Ill., a corporation of Illinois

Application August 25, 1949, Serial No. 4,689

Term of patent 14 years

(Cl. D66—2)

To all whom it may concern:

Be it known that I, George B. Dorey, a citizen of the Dominion of Canada, residing at Westmont, Province of Quebec, Dominion of Canada, have invented a new, original, and ornamental Design for Head for Gate Operating Mechanism for Hopper Cars, of which the following is a specification, reference being had to the accompanying drawing, forming a part thereof.

Figure 1 is a top plan view of a head for gate operating mechanism for hopper cars showing my new design;

Figure 2 is a view in side elevation of the head shown in Figure 1;

Figure 3 is a view in end elevation at the left hand end of Figures 1 and 2;

Figure 4 is a view in end elevation at the right hand end of Figures 1 and 2.

I claim:

The ornamental design for a head for gate operating mechanism for hopper cars, as shown.

GEORGE B. DOREY.
